WIRE STRETCHER

Jacob M. Haynes, Macksville, Kans.

Application November 30, 1935, Serial No. 52,425

3 Claims. (Cl. 254—161)

This invention relates to a wire tightener or stretcher particularly designed for permanent installation as part of a clothesline to enable instant tightening of the line through the turning of a crank.

It aims to provide a novel, simple, and durable construction, particularly wherein novel means are employed to cause the tightened portion of the wire to coil evenly over a portion of the tightening or crank shaft, and at a certain limit to reverse the direction of coiling, in order to accommodate the excess portion within minimum space.

The more specific objects and advantages will become apparent from a consideration of the description following taken in connection with accompanying drawing illustrating an operative embodiment.

In said drawing:—

Figure 1 is a view in elevation showing the improvements in use;

Figure 2 is a view taken at a right angle to Figure 1;

Figure 3 is a longitudinal sectional view taken on the line 3—3 of Figure 1; and

Figure 4 is a transverse sectional view taken on the line 4—4 of Figure 1.

Referring specifically to the drawing, 10 designates a frame which may consist of two metallic bars or strips 11 riveted together as at 12. This frame is adapted to be anchored to any suitable support by means of a wire or the like 13, passing through registering openings 14 in one end of the bars 11.

At the opposite end, bars 11 are separated or deflected away from each other to provide bearing portions 15 in which a reel shaft 16 is journaled, which shaft has a crank 17 and an operating handle 18.

Rigidly mounted in any suitable way on the reel shaft 16, between and adjacent one of the bearing portions 15, is a wire bending, holding, and adjusting guide block 18, the same having a deep worm or spiral groove as at 19 in the base of which is an opening 20 for one end of the wire 21 constituting the clothesline, and which opening 20 may be extended into the reel shaft 16, as at 22, if desired. Also located between the bearing portions 15 is an annular plate or washer 23, a cotter key 24 preferably being interposed between the same and adjacent bearing portion 15, which is secured in an opening 25 in the reel shaft 16.

It will thus be seen that the clothesline 21 is adapted to be anchored at one end to any stationary support and at the other end to be anchored in the holes 20 and 22, while the frame 10 is anchored to a stationary support by the wire

13. After the reel shaft 16 is given one half a turn through operation of the crank 17, the wire 21 will be anchored in the openings 20 and 22. Thereafter the reel shaft 16 may be turned whenever desired to properly tension the clothesline, the groove 19 facilitating the bending and holding of the clothesline and causing the same to evenly coil along the reel shaft 16. When the coils are sufficient in number to engage the washer or plate 23, the latter will deflect them in the opposite directions to superpose the same on the coils in direct engagement with the reel shaft 16. The excess clothesline may thus be accommodated within minimum space.

Means are provided to hold the crank 17 and shaft 16 at the various degrees of adjustment and may comprise a hook 26 having one end curled at 27 and pivotally passing through an opening 28 in the frame, the opposite ends thereof being a hook 29, engageable with the crank 17.

Various changes may be resorted to provided they fall within the spirit and scope of the invention.

I claim as my invention:—

1. A device of the class described, comprising a frame having separated end portions, a reel shaft journaled in said end portions, a wire bending, and holding guide block of ring form on said shaft between said portions having a spiral groove nearer one end portion than the other end portion, and said block and reel shaft having aligned wire-anchoring openings communicating with the groove.

2. A device of the class described, comprising a frame having separated end portions, a reel shaft journaled in said end portions, a wire bending, and holding guide block of ring form on said shaft between said portions having a spiral groove nearer one end portion than the other end portion, said block and reel shaft having aligned wire-anchoring openings communicating with the groove, and a coil-deflecting and reversing member on said shaft.

3. A device of the class described, comprising a frame having separated end portions, a reel shaft journaled in said end portions, a wire bending, and holding guide block of ring form on said shaft between said portions having a spiral groove nearer one end portion than the other end portion, said block and reel shaft having aligned wire-anchoring openings communicating with the groove, a coil-deflecting and reversing member on said shaft, a cotter passing through said shaft between the member and adjacent portions, said frame comprising a plurality of bars fastened together, and crank means to operate said shaft.

JACOB M. HAYNES.
